(57) **CLAIM**

The ornamental design for a milk storage bag, as shown and described.

DESCRIPTION

FIG. 1 is a perspective view of a milk storage bag, showing my new design;

FIG. 2 is a front view of the milk storage bag;

FIG. 3 is a rear view of the milk storage bag;

FIG. 4 is a left-side view of the milk storage bag;

FIG. 5 is a right-side view of the milk storage bag;

FIG. 6 is a top plan view of the milk storage bag;

FIG. 7 is a bottom plan view of the milk storage bag; and, FIG. 8 is a perspective view of the milk storage bag in an open configuration.

Any shading are not features of the design but are utilized to illustrate the surface contours of the milk storage bag in the drawings.

The broken lines in the drawings depict portions of the milk storage bag that form no part of the claimed design.
